TEXTILE DRAFTING MECHANISM

Gordon C. Anderson, Biddeford, and Garfield B. Ingraham, Falmouth, Maine, assignors to Saco-Lowell Shops, Boston, Mass., a corporation of Maine

Application December 19, 1955, Serial No. 553,775

5 Claims. (Cl. 19—135)

This invention relates to textile drafting elements of the type used on spinning and roving frames and more particularly to novel supporting and weighting structures for the drafting rolls of such elements.

In application Serial No. 487,912, filed February 14, 1955, now Patent No. 2,750,340, is shown and described a drafting element top roll supporting and weighting structure of the type having an overlying support member with a plurality of top roll weighting arms mounted thereon for engaging the top rolls, said arms being mounted for lateral swinging movement to permit self-alinement of the rolls and being loaded by means of coil compression springs interposed between said arms and the overlying support member. Although such structure is entirely satisfactory in cases where conventional weighting forces are to be applied to the rolls, it has been found that where high weighting forces of the order of 40 pounds are used, as particularly on the front rolls of high draft spinning and roving frames, slight errors in the manufacture of springs or other components occasionally cause side forces to be applied to the mounting arms of sufficient magnitude to cause initial lateral misalignment of the arms great enough to prevent self-alinement of the rolls.

Accordingly, it is an object of the present invention to provide novel means for adjustably correcting the side force producing errors of such compression springs or other components so that self-alinement of even heavily weighted rolls readily takes place.

For the purpose of more fully describing further features and objects of the invention, reference is now made to the following specification wherein is described preferred embodiments thereof, together with the accompanying drawings.

In the drawings:

Fig. 1 is a cross-sectional side elevation of a drafting element top roll supporting and weighting structure having the novel means of the invention for adjustably correcting compression spring side force producing errors;

Figs. 2 and 3 are enlarged end and side elevational views respectively, showing a first embodiment of the means of this invention;

Fig. 4 is an isometric view of a part of the means of Figs. 2 and 3;

Figs. 5 and 6 are enlarged end and side elevational views respectively, showing a second embodiment of the means of this invention; and

Fig. 7 is an isometric view of a part of the means of Figs. 5 and 6.

Referring to the drawings, the construction therein shown comprises bottom front and rear rolls 2 and 3, respectively, suitably mounted in bearings on the frame of the machine, top rolls 4 and 5 cooperating with said respective bottom rolls to perform the drafting operation, and an intermediate control mechanism including a bottom roll 6 driving an apron 7, the latter being guided over an apron bar 8 and held stretched by the usual tension pulley (not shown). A top roll 12 supported by the

2

apron bar 8 and the bottom roll 6 depresses the apron 7 therebetween, the degree of such depression being determined by adjustment of the horizontal spacing between the slides (not shown) supporting the apron bar 8 and bottom roll 6 respectively.

The top rolls 4, 5, and 12 are weighted by an overlying cantilever sheet metal support member of generally inverted U shape with a top 14 and sides 16 mounted for vertical swinging movement about a fixed shaft 18 on the machine frame at the rear portion thereof. Said support member is normally positioned rigidly over the bottom rolls 2, 3, and 7 by means of a toggle mechanism, but such mechanism may be released and the support member swung upwardly in a vertical plane about its shaft 18 to provide access to the drafting frame.

In order to support and weight the front and intermediate top rolls 4 and 12, a long rear arm comprising a pair of side members 20 and a front interconnecting member 22 is provided. The side members of said arm are mounted on a shaft 24 extending between support member sides 16 at the rear end thereof for pivotal movement in a vertical plane. The rear arm extends forwardly in a generally parallel relationship to the support member with its side members 20 inside of and closely adjacent to sides 16 thereof to engage its forward longitudinally extended end connecting member 22 with the arbor of intermediate top control roll 12. Extending transversely between the side members 20 of said long rear arm is a shaft 26 having therein a vertically extending tapped hole for receiving the threaded portion of adjusting screw 28. The upper portion of said screw extends freely through a hole in the top 14 of the overlying support member and has an enlarged head of greater diameter than that of said hole adapted to engage said top and so limit the extent of downward travel of said arm.

The lower end of said screw loosely supports the rear end of forward arm 30 which arm extends forwardly in a generally parallel relationship to the support member to engage its forward end bearings with the arbor of front top roll 4. The loose support is provided by a ball bearing 32 mounted on the end of screw 28 beneath the arm 30 to permit transverse swinging movement for self-alinement of the rolls as well as vertical swinging movement. The forward arm passes above the forward interconnecting end member 22 of the rear arm and is out of contact therewith. In order to provide loading pressure for the top rolls 4 and 12 engaged by the first and second arms respectively, a pair of helical coil compression springs 34 are interposed between the upper surface of forward arm 30 and the lower surface of top 14 of the support member thereon, such springs pressing downwardly on said arms to engage said top rolls with their cooperating bottom rolls.

According to the present invention, a rotatably adjustable member such as a circular washer generally designated 36 is provided for correcting side force errors of springs 34 due to manufacturing inaccuracies of said springs or other components, as for example, with a spring, end faces not perpendicular to the axis of the spring, and/or end faces not parallel to one another or with other components, top 14 and arm 30 not perpendicular to the spring axis, for instance. Such members 36 are preferably positioned adjacent the end of springs 34 between the lower ends of said springs and the upper surface of arm 30 and are adapted to be rotated to tilt or move the spring end for alinement of the arms after the drafting element has been installed in a spinning or roving frame so that the rolls will readily self-align.

More specifically, and referring to Figs. 2 through 4, as a first embodiment, such a washer 36 may have a slanted or wedge-shaped upper spring seating face 38 with a cen-

tral coaxial upstanding circular lug 40 thereon fitting within the lower end of spring 34 for positioning it. As a second embodiment, the washer 36 may have a flat upper spring seating face 38' with upwardly extending circular lug 40' positioned eccentrically thereto on said spring seating surface. In either case, such washer is rotatably positioned on the upper surface of arm 30 by a rotatable coaxial downwardly extending circular lug 42 which fits into a cooperating hole 44 in arm 30, and a central hole 46 is provided in washer 36 for engagement by a suitable wrench for rotating the washer to a desired position. The upper end of springs 34 are positioned on the lower surface of support member top 14 by downwardly extending lugs 48 therein, and a suitable hole 50 is provided in each of said lugs for access to washer 36 by said wrench.

The rear top roll 5 is supported and weighted by a short third arm 52 loosely mounted by a ball bearing 54 for both vertical and horizontal swinging movement on a bracket 56 attached to top 14 of the support member by means of a screw 58 longitudinally adjustable in a slot 60 therein, and is provided with suitable bearings for engaging the arbor of rear top roll 5. A loading spring 62 is interposed between the upper surface of arm 52 and the lower surface of bracket 56 to engage said roll in cooperating relationship with its bottom roll 3.

Preferably, a rotatably adjustable washer 36' as hereinbefore described is provided interposed between the end of spring 62 and arm 52 for correcting side force producing errors of said spring on the arm 52, although such is not as important as on the forward rolls 4 and 12 due to the substantially lower loading employed on back roll 5. As shown, the rear washer 36' must be rotated from below rather than above.

In operation then, the supporting and weighting member 14, when locked into operative position overlying bottom rolls 2, 3, and 6, provides a rigid cantilever support against which loading springs 34 and 62 will be compressed to engage the top rolls with their respective bottom rolls.

The forces imposed on the weighting arms 20, 30, and 56 due to the inaccuracies in the manufacture of springs and other parts 34 and 62 can be corrected by rotating washers 36 and 36', respectively, by a suitable wrench until the undesirable lateral forces are no longer present as will be indicated by the central alinement of the rolls, it being understood that forward or rearward tilting or displacement of springs 34 and 62 will not affect lateral alinement so that the degree of correction can be varied between a maximum and zero to achieve the desired value. Thus, as shown in Fig. 2, tilting of the roll and of a spring by washer 36 will tend to bulge it to provide a desired degree of correction, while sidewise displacement of a roll and of a spring, as shown in Fig. 5, will tend to tilt it to provide the desired degree of correction.

Thus it will be seen that the invention has provided a novel drafting element top roll weighting and supporting arrangement wherein uniform adjustment for initial self-alinement may be achieved irrespective of the manufacturing inaccuracies of the coil springs or other components employed with the structure as loading means. The term "rolls" as used herein is intended to include known fiber control elements such as, for example, of the overlying

short apron type wherein the weight is applied to the supporting cage rather than directly to the top roll associated therewith. Various other modifications of the invention within the spirit thereof and the scope of the appended claims will occur to those skilled in the art.

We claim:

1. In a supporting and weighting structure for the top rolls of textile drafting mechanisms wherein a support member extends over at least one pair of top rolls, a weighting arm for said top rolls mounted on said support member for self-aligning swinging movement, coil spring loading means interposed between said arm and said support member, and means positioned at one end of said coil spring and mounted for rotation independently thereof for correcting side force producing errors of said spring loading means causing lateral misalignment of said arm.
2. In a structure as claimed in claim 1 wherein said means for correcting includes wedge means positioned at one end of said coil spring to tilt said spring end.
3. In a structure as claimed in claim 1 wherein said means for correcting includes eccentric means positioned at one end of said coil spring to move said spring end.
4. In a supporting and weighting structure for a textile drafting mechanism having a plurality of pairs of top and bottom rolls positioned to act successively on a sliver, a support member overlying said bottom rolls, a plurality of weighting arms supported on said member in generally parallel relationship thereto for limited self-aligning swinging movement, coil spring loading means interposed between said member and said arms for pressing a top roll engaged by an arm into cooperating relationship with its respective bottom roll, and a wedge member with a plane slanted spring seating face mounted for rotation independently of said coil spring cooperating with one end of said coil spring for correcting side force producing errors of said coil spring loading means causing lateral misalignment of said arm by rotation of said member to tilt said spring end.
5. In a supporting and weighting structure for a textile drafting mechanism having a plurality of pairs of top and bottom rolls positioned to act successively on a sliver, a support member overlying said bottom rolls, a plurality of weighting arms supported on said member in generally parallel relationship thereto for limited self-aligning swinging movement, coil spring loading means interposed between said member and said arms for pressing a top roll engaged by an arm into cooperating relationship with its respective bottom roll, and an eccentric member mounted for eccentric rotation independently of said coil spring cooperating with one end of said coil spring for correcting side force producing errors of said coil spring loading means causing lateral misalignment of said arm by rotation of said member to displace said spring end.
